UNITED STATES PATENT OFFICE.

CHARLES F. ANNAN, OF BOSTON, MASSACHUSETTS.

RAILWAY-CAR.

SPECIFICATION forming part of Letters Patent No. 279,311, dated June 12, 1883.

Application filed October 5, 1882. (No model.)

To all whom it may concern:

Be it known that I, CHARLES F. ANNAN, of Boston, in the county of Suffolk and State of Massachusetts, have invented certain new and useful Improvements in Railway - Cars, of which the following is a specification.

This invention has for its object, first, to enable the weight of a car and its load to assist in starting the car and keeping it in motion after it is started; secondly, to enable the weight of the car and its load to assist in braking or retarding the motion of the car when desired; and, thirdly, to enable the car to be stopped or retarded in its motion more positively by the combined action of its weight and of direct-acting brakes applied to the peripheries of its wheels.

To these ends my invention consists in the improvements which I will now proceed to describe and claim.

Of the accompanying drawings, forming a part of this specification, Figure 1 represents a sectional elevation of a car-supporting frame-work and wheels embodying my invention. Fig. 2 represents a bottom plan thereof. Fig. 3 represents an outside elevation of one of the primary wheels. Fig. 4 represents an inside elevation of the same, showing the secondary wheel having an internal bearing upon the flange of the rim of the primary wheel, and at one side forward of the vertical axis of the same. Fig. 5 represents a vertical section of the same when the axes of both are in the same vertical plane. Fig. 6 shows a sectional elevation of the car-supporting frame-work and wheels with brakes attached to the frame-work. Fig. 7 represents a bottom plan of the construction shown in Fig. 6.

The same letters of reference indicate the same parts in all the figures.

In carrying out my invention I provide a primary frame, A, of suitable construction, and mount the same upon primary wheels D, adapted to run upon the track, and having axles C, which are journaled in suitable bearings or pedestals, B, attached to the primary frame. Each primary wheel D has on its inner side an internal flange, I, said flanges constituting curved tracks or supports for the secondary wheels hereinafter described.

E represents a secondary frame, which di-

rectly supports the body of the car, and is mounted on secondary wheels H, which bear on the flanges I of the primary wheels, and are free to move back and forth thereon independently of said primary wheels, the secondary wheels H being attached to tubular axles F, which inclose the axles C of the primary wheels, and are of sufficient size to permit the secondary wheels to move upon the curved tracks or flanges I to any extent required without interfering with the axles C. The secondary frame E is provided with bearings or pedestals G, in which the tubular axles F are journaled. (See Fig. 5.) It will be seen, therefore, that while the primary frame and its wheels are adapted to move upon the track in the usual manner, the secondary frame and its wheels are adapted to move independently of the primary frame on the curved tracks or flanges I, so that the weight of the secondary frame and its load can be caused to bear on said flanges either in front or at the rear of the vertical planes of the axles of the primary wheels, and thus either rotate the primary wheels or check their rotation, as the case may be, the primary wheels being rotated when the weight of the secondary frame and its load bears on the flanges I at points in front of the vertical planes of the axles C, and retarded or stopped when said weight bears on the flanges I at points in the rear of said planes. The primary and secondary frames are connected by levers J J, pivoted at a a to the secondary frame. The levers J J have shorter and longer arms, the latter being preferably about six times as long as the former. The shorter arms are connected by pins b b to the primary frame, said pins passing through slots in the levers.

K K represent draw-rods connected by chains to the longer arms of the levers J and extending to the ends of the car. The horse or other power employed to draw the car is applied to one of the draw-rods or the other, according to the direction in which the car is to move. When the car is at rest the centers of the primary and secondary wheels are in the same vertical planes, and the weight of the car-frame and its load has no effect on the primary wheels. When power is applied to one of the draw-rods the levers J J are turned on their pivots or fulcrums and caused to move

the frames A E with reference to each other, the wheels of the secondary frame E being thus caused to bear on the flanges I at points in front of the vertical planes of the centers of the primary wheels, as shown in Figs. 1 and 6, and rotate said primary wheels in the direction required to move the car forward. This relative movement takes place before the entire weight of the load is felt by the power; hence in starting the car much less power is required than would be required to move the entire load, a marked gain in power being obtained by the levers J J, arranged as described. So long as the power is exerted on the draw-rods the levers J J will keep the primary and secondary frames in the same relative positions, so that the weight of the secondary frame and its load will constantly aid in moving the car forward.

To enable the driver or other attendant to reverse the described relative movements of the frames and cause the weight of the secondary frame to bear on the flanges I at points in the rear of the primary wheels, and thus retard or stop the movement of the car, I provide the secondary frame with brake-rods M M, connected by chains L L to the primary frame. By winding the chain L at the forward end of the car upon its brake-rod the secondary frame E will be moved backwardly to effect the result last described.

N N, Figs. 6 and 7, represent brake-shoes secured by brackets or hangers n n to the frame A, and connected by crossed rods P P to the secondary frame. There are two sets of brake-shoes N for each pair of primary wheels, one set being for use when the car is moving in one direction, and the other when the car is moving in the opposite direction.

When the operator desires to stop the car more quickly and positively than by the weight of the secondary frame, as last described, he operates the brake-rods and chains so as to move the secondary frame farther backward, and thus bring one set of brake-shoes to bear upon the peripheries of each pair of primary wheels. Two systems of brakes are thus simultaneously brought into use—viz., the weight of the secondary frame and its load and the direct-acting brakes N. The operator is thus enabled to stop the car even on steep grades without that torsional strain on the car-axles caused by the application of brakes only to a single point on the surface of each wheel in the usual manner. The brake-shoes N do not require to bear with such a degree of pressure against the wheels as they would if said shoes alone were relied on to brake the car.

I am aware that a car has been before provided with a primary frame having internally-flanged wheels adapted to run on a track, and a secondary frame having smaller wheels adapted to run on the flanges of the primary wheels, the secondary frame supporting the load and being movable independently of the primary frame; but in the only instance of such use of which I am aware, there has been no connec-

tion between said frames such as is afforded by my levers J J, and therefore the secondary frame and its load is moved forward only after the primary frame has started, and thus caused the wheels of the secondary frame to roll forward by gravitation. My lever-connections, on the other hand, acted on by the power which draws the car, cause the secondary frame to move forward before the primary frame moves, and thus assist in moving the primary wheels instead of being first lifted by the primary wheels, as heretofore. Therefore, while I do not claim, broadly, the subject-matter above acknowledged to be old,

What I claim is—

1. In a car, the combination of a primary frame mounted on primary wheels D, adapted to run on the track, a secondary load-supporting frame mounted on secondary wheels, which bear on internal flanges on the primary wheels, and are movable on said flanges with said secondary frame independently of the primary frame and its wheels, lever-connections, substantially as described, between the primary and the secondary frame, and means for applying to said lever-connections the power used to draw the load, whereby said power is caused to move the wheels of the secondary frame forward of the vertical planes of the centers of the primary wheels D before starting the latter, as and for the purpose set forth.

2. In a car, the combination of a primary frame mounted on primary wheels D, adapted to run on the track, a secondary load-supporting frame mounted on secondary wheels, which bear on internal flanges or curved tracks on the primary wheels, and are movable with said secondary frame independently of the primary frame, lever-connections, substantially as described, between the primary and the secondary frame, and devices, as described, whereby an attendant on the car is enabled to move the secondary frame and its load backwardly with relation to the primary frame, and cause the wheels thereof to bear on the primary wheels at points back of the vertical planes of the centers of the primary wheels, thereby breaking or retarding the movement of the car, as set forth.

3. In a car, the combination of a primary frame mounted on primary wheels D, adapted to run on the track, a secondary load-supporting frame mounted on secondary wheels, which bear on internal flanges or supports on the primary wheels, and are movable with said secondary frame independently of the primary frame, lever-connections, substantially as described, between said primary and the secondary frame, devices, as described, whereby an attendant on the car is enabled to move the secondary frame and its load backwardly to brake or retard the car, and direct acting-brakes N, adapted to bear on the primary wheels when the secondary frame is moved sufficiently by the operator, as set forth.

4. The combination of the primary frame A,

mounted on wheels D, having internal flanges, I, the secondary frame E, mounted on wheels H, supported by said flanges, and having hollow axles inclosing the axles of the wheels D, the 5 levers J J, connected, as described, to the frames A E, and the draw-rods K, connected to the longer arms of said levers, as set forth.

5. The combination of the primary frame A, mounted on internally-flanged wheels D, the 10 secondary frame E, mounted on wheels H, supported by said internal flanges, and having hollow axles inclosing the axles of the wheels D, the levers J J, connecting the frames A E, and the brake-rods M and chains L, all arranged 15 and operated substantially as described.

6. The combination of the primary frame A, mounted on internally-flanged wheels D, the secondary frame E, mounted on wheels H, supported by internal flanges, and having hollow axles inclosing the axles of the wheels D, the 20 levers J J, connecting the frames A E, the brake-rods M and chains L, and the brake-shoes N, secured to the frame A, and connected by rods P with the frame E, all arranged and operating substantially as described.
